UNITED STATES PATENT OFFICE.

JAMES N. HEALD, ROGER N. HEALD, AND EDWARD M. TAYLOR, OF WORCESTER, MASSACHUSETTS, ASSIGNORS TO THE HEALD MACHINE COMPANY, OF WORCESTER, MASSACHUSETTS, A CORPORATION OF MASSACHUSETTS.

GRINDING MACHINE.

Application filed June 13, 1927. Serial No. 198,484.

The present invention relates to automatic grinding machines, of the type employed for surface grinding, and more especially wherein the faces of successive small flat articles, such as piston rings, washers, ball races and the like, are subjected to the action of a grinding wheel. More specifically, the invention relates to that class of grinding machines disclosed, for example, in the patent to Littman, No. 1,361,883, granted December 14, 1920, and the patent to Law, No. 1,582,481, granted April 27, 1926, wherein the workpieces, stacked in a magazine, are successively transferred to the grinding position and ultimately discharged from the machine by the intermittent rotation of a work carrier plate.

The invention contemplates improvements in mechanism of this class, including an accurate driving mechanism for the work carrier, and one that will subject the parts to no appreciable strain. Means are also provided to locate each successive workpiece very accurately on the revolving chuck, which is used to hold the work in grinding position.

Another object of the invention is to prevent the formation of scratches on the under face of the workpiece (which in a great many cases have already been finished); said scratches resulting, in prior machines, from the rotation of the work carrier under the bottom workpiece, which presses heavily against said carrier due to the combined weight of all the articles in the magazine. To that end the invention provides means to hold the stack of articles firmly in the magazine, and to lift them slightly above the level of the carrier, except at such times when the carrier is stationary and the lowermost workpiece is free to drop into the proper conveying aperture of the carrier. According to the invention, the pressure employed to grip the articles during this lifting action, is limited to what is necessary for the purpose, in order that the articles may not be deformed.

The above and other advantageous features of the invention will hereinafter more fully appear, reference being had to the accompanying drawings, in which—

Fig. 1 is a side elevation of a grinding machine, built in accordance with the invention, certain parts being broken away to show the construction of the novel mechanism.

Fig. 2 is a fragmentary front elevation, cer-

tain parts being removed, showing a cam that controls the magnetic chuck circuit.

Fig. 3 is a detail sectional view, on an enlarged scale, of the actuating mechanism for the work carrier, the section being taken on the line 3—3 of Fig. 2.

Figs. 4, 5, 6 and 7 are sectional views taken respectively on the lines 4—4, 5—5, 6—6, and 7—7 of Fig. 3.

Fig. 8 is a developed view of the work carrier actuating cam.

Figs. 9 and 10 are respectively front and side elevations of the work holding magazine and the mechanism to lift the stack of workpieces in said magazine, these parts being shown detached from the machine.

Fig. 11 is a fragmentary plan view, showing the automatic chuck-elevating feed that compensates for the wear of the grinding wheel.

Fig. 12 is a front elevation of the parts shown in Fig. 11.

Fig. 13 is an enlarged fragmentary view of certain parts shown in Figs. 11 and 12.

Fig. 14 is an enlarged sectional view taken on the line 14—14 of Fig. 11.

Fig. 15 is a vertical sectional view taken on the axis of the magnetic chuck, and showing the chuck driving and elevating mechanisms.

Fig. 16 is a fragmentary elevation of the left hand side of the machine, showing a cam operated valve mechanism that controls the operation of the work carrier.

Fig. 17 is a fluid pressure or piping diagram.

Fig. 18 is a plan view of the work carrier plate.

Figs. 19 and 20 are diagrammatic views showing the stack lifting operation.

Like reference characters refer to like parts throughout the drawings.

Referring first to Fig. 1, the machine is mounted on a base 1 which provides ways, not shown, for the horizontal reciprocation and adjustment of a carriage or table 2. The carriage 2 provides inclined ways 3 for the travel thereon, in a manner that will presently be described, of a grinding wheel head 4. The grinding wheel 5 is carried by the head 4, being mounted on a spindle 6 which is journaled in said head. The grinding wheel may be rotated in any suitable manner; as shown in broken lines in Fig. 1,

the shaft 6 provides a drum 7, which is driven from a main drive shaft 8 by means of a pulley 9 on said shaft and a belt 10. To provide for the slight rise and fall of the head 4, due to its travel on the inclined ways 3, a heavy idler pulley, not shown, is employed, but these parts, being well known in machines of this character, need not be further described.

- 10 The workpiece holding magazine, the work carrier which successively transfers individual workpieces to grinding position, and the rotating magnetic chuck, which holds and rotates the workpiece in said position, are 15 all carried by a separate machine unit 11, which is mounted for vertical adjustment with respect to the base 1, on slidways 12, a hand wheel 13 being provided to raise or lower the unit 11 at will. As shown in Fig. 20 15, the magnetic chuck 14 is mounted on the top of a spindle 15, which is carried in bearings 16 and 17 provided by the unit 11; said chuck 14 and spindle 15, as in the case of the wheel 5 and spindle 6, may be rotated in any 25 suitable manner; the drive shown being obtained through a worm wheel 18, fastened to the spindle 15, that meshes with a driving worm 19, the latter being mounted on a shaft 20 which, as indicated in dotted lines in Fig. 30 1, ultimately derives its rotation from the aforesaid main drive shaft 8. A universal joint 21 is provided to maintain the drive despite relative vertical adjustment of the unit 11.
- 35 The machine of the present invention, in common with that disclosed and claimed in a copending application of Heald and Law, Serial No. 84,881, filed January 30, 1926, contemplates an inclined reciprocatory motion 40 of the head 4, whereby to bring the grinding wheel down upon the surface of the rotating workpiece with full face contact. As in said Heald and Law machine, the grinding wheel 5 travels downwardly, for the grinding of 45 each successive workpiece, to a definite level, so that each workpiece may be ground to the same depth; this necessitates the timing of the work carrier mechanism, to transfer successive workpieces to grinding position, in 50 accordance with the motion of the grinding head 4 on the inclined ways 3.

Still referring to Fig. 1, the driving means for the head 4 is herein shown as a motor 22 mounted on the carriage 2 which, by means of pulleys 23 and 24 and a belt 25 drives a shaft 26 at reduced speed. A worm 27 on the shaft 26 meshes with and drives a worm wheel 28 on a shaft 29. By means of a cam, not shown, carried on the shaft 29 the grinding head 4 is given its reciprocatory motion on the inclined ways 3, and this mechanism, as well as the adjustment means to control the depth of cut and to vary the length of time during which the head 4 dwells at its lowered position, need not be further described herein,

since it forms no part of the present invention. Each reciprocation of the head 4, for the reasons above stated, must be accompanied by a definite angular movement of the work carrier plate 30. Referring to Fig. 16, which 70 shows the opposite side of the machine from that shown in Fig. 1, the shaft 29 provides a cam 31 at each revolution of which a cam portion 32 comes in contact with a lever 33, or a suitable roller 34 provided thereby. The 75 lever 33 is pivoted at 35; at a point 36 spaced from the pivotal point 35 but on the same level, is pivoted an arm 37. The arm 37 is of the same length as one arm of the lever 33, and the ends of said lever and said arm are 80 connected by a bar 38 which, as will be readily seen, must always be horizontal. This mechanism is provided because, as will hereinafter appear, the carriage 2 is preferably given a limited reciprocatory traverse, and at all 85 events it is adjustable longitudinally with respect to the base 1.

The bar 38, when depressed by the action of the cam portion 32 acting through the levers described, moves a lever 39 pivoted at 40 on 90 the machine base 1; the lever 39 is connected at 41 to a valve member 42 which causes fluid pressure actuation of the carrier 30.

As shown in the fluid pressure diagram of Fig. 17, fluid under pressure may be supplied 95 from any convenient source, such as the pump 43. The fluid is led by a supply line 44 to the fluid entrance port 45 of a valve casing 46 in which the valve member 42 is located. Fig. 17, although diagrammatic as to the relative position of the units in the fluid pressure system, shows the valve casing 46 in true section; said valve casing provides two chambers 47 and 48 at opposite ends thereof, 100 these chambers being in communication with each other and with the fluid entrance port 45 by means of a passage 49. The valve casing 46 also provides chambers 50 and 51 adjacent the chambers 47 and 48, and a centrally located chamber 52. A continuous hole 110 is made right through the casing 46, passing through all the aforesaid chambers, the valve member 42 being located therein. The member 42 is formed out of a cylindrical piece whose diameter is the same as the diameter of 115 the hole through the several chambers. But at 53 and 54 the diameter of the valve 42 is reduced; this leaves a central portion 55 of the main diameter. It follows that when the valve member 42 is in its normal raised position shown in Fig. 16, (where it is ordinarily maintained by means of a coil spring 40 surrounding the pivot 40 and connected to the base 1 and the lever 39, respectively), the chamber 50 is connected to the chamber 47, 120 while the chamber 51 is connected to the chamber 52 and disconnected from the chamber 48. When the valve member 42 is depressed, as described, the chamber 51 is connected to the chamber 48, and the chamber 50 125 130.

is connected to the chamber 52, and in this position the parts are shown in Fig. 17.

The chambers 50 and 51 connect, by means of flexible piping 56 and 57, respectively, to the opposite ends of a generally semi-circular chamber 58. The construction of said chamber is shown in Figs. 3 and 5; it is located, as shown in Fig. 1, in the unit 11, and a horizontal shaft 59 extends through it, the axis of the shaft being located at the center of the circle whose arcuate portion forms one boundary wall of the said chamber as it is seen in cross section. A sleeve 60 surrounds the shaft 59, and this sleeve extends through the right hand wall of the chamber, as it is viewed in Figs. 1 and 3. To this sleeve 60 is fastened in any suitable manner an arm 61, which contacts with the plane surfaces which form the side walls of the chamber and the outer end of which terminates in an arcuate portion of the same radius as the said circle and lies close to it, so as to allow free movement but prevent the free passage of fluid. It will readily be seen that the chamber 58 is, in this manner, divided into two portions, and whenever the pressure fluid is made active, for example, by way of the piping 57 thereby to enter the chamber 58 through the port 57^a, then the arm 61 will be rotated clockwise from the position shown in Fig. 5 to the position indicated in Fig. 17, the sectional view of the chamber 58 in the latter figure being taken looking in the opposite direction, while whenever fluid is admitted via the port 56^a through the piping 56, the arm will be rotated counterclockwise to the other extreme position.

The movement of the valve member 42, which is mechanically actuated in timed relation to the reciprocations of the grinding head 4 as described, is thus made use of to cause fluid pressure actuation of the arm 61; when the cam portion 32 acts to depress the valve member 42, the fluid flows from the pump 43, by way of the piping 44 and entrance port 45, to the chamber 48, thence past the reduced portion 54 of the valve 42 to the chamber 51, thence by the piping 57 to the port 57^a. The movement of the arm 61 forces fluid out of the chamber 58 by way of the port 56^a whence, by the piping 56 and chamber 50, it passes the reduced portion 53 of the valve 42 and exits by means of piping 52^a to the usual storage tank which is provided in this class of machines for the fluid. Immediately thereafter, the cam portion 32 moves beyond the roller 34 on lever 33, and the valve member 42 is raised; this reverses the direction of flow of the fluid in the piping 56, 57 and moves the arm through 180° back to its original position, as will be readily apparent without further description. Thus for each revolution of the shaft 29 which controls the reciprocation of the head 4, the arm 61 is given a double oscillation through 180°, and

this causes an angular movement of the work carrier plate 30, always in the same direction of rotation, as will now be described.

On the sleeve 60, outside the chamber 58, is fastened a member 62, which therefore partakes of the angular motion of said sleeve given it by the motions of the arm 61. The member 62 provides a radially extending portion 62^a, to which is pivotally attached at 63 a pawl 64. See Fig. 6. The pawl 64 is pressed by a spring 65 against a member 66, which has a pair of ratchet notches 67, 67 cut in its periphery, said notches being 180° apart. Figures 3 and 6 should be compared in order to understand the relation of these parts. The oscillations of the member 62, therefore, turn the member 66 through 180° in a clockwise direction as viewed in Fig. 6, which is a section taken looking to the right in Fig. 3, and the member 66 is accurately positioned and prevented from reverse turning in consequence of the dragging action of the pawl 64 by means of a spring pressed pin 68, which seats in V notches 69, 69 formed in the periphery of the member 66 and likewise spaced 180° apart. The member 66 is fastened to the shaft 59, as is likewise a cam member 70 cut from a cylinder. It will be seen at each oscillation of the arm 61, the shaft 59 and the cam members 70 are turned exactly 180°, always, however, in the same direction of rotation.

As shown in Figs. 1 and 3, the carrier plate 30 is supported on a stationary plate 71, which provides a recess 72 for the reception of the magnetic chuck 14, and another recess, not shown, for the discharge of the finished workpieces. The plate 71 is supported by three rods 71^a inserted in bosses on the underside thereof, the other ends of said rods being inserted in three bosses, which are part of the stationary unit 11, and rest on three set screws 71^b, for the purpose of adjusting the height of the plate to suit the chuck. A boss 73 formed in the stationary frame of the unit 11 acts as a guide for the hub of a disc 75, said hub having a vertical shaft 74 slidably keyed therein for the purpose of being readily adjustable to suit various thicknesses of transfer plates. The disc 75 is best shown in Figs. 3 and 7, and provides four rollers 76 projecting from its lower side, these rollers being spaced 90° apart. As the cam member 70 revolves, the cam portion thereon enters between two rollers, the side portions 70^a and 70^b of the cam being spaced so as to fit between any two rollers with practically no play. This revolves the plate 75 through 90°, and consequently the carrier plate 30 is revolved by the same amount.

Referring to Fig. 18, in connection with Fig. 3, the carrier plate 30 provides, removably, four ring-like inserts 77, each one having an aperture 78 for the reception of the

workpieces. By simply replacing the inserts 77 with others providing different sized apertures, any size of round workpiece (within limits, of course) can be handled. The workpieces are stacked between three posts 79, 80 and 81, which constitute a magazine. As the carrier plate revolves, the workpieces drop into the apertures one at a time being supported by the underlying stationary plate 71; the workpieces are thus moved one station at a time, being ground when they reach the magnetic chuck which is located, as aforesaid, at the recess 72; finally, being moved off of the magnetic chuck, they are discharged through a hole in the plate 71. The foregoing cycle of operation will be found described in the patent to Littman referred to, but is briefly recapitulated in order that the present invention may be better understood.

Referring to Figs. 1, 9 and 10, the magazine is lifted before each turning movement of the carrier 30; to accomplish such lifting, the post 80 is pressed in the direction of the posts 79 and 81, thus gripping all the workpieces in the magazine. The amount of the gripping force is dependent on the weight of the magazine including its contents, and thus when there is, for example, but one thin walled workpiece left in the magazine, it will not be distorted by the pressure, while when there are a great many heavy workpieces in the magazine, the pressure will be adequate to hold their combined weight. The foregoing is embodied in the following mechanism:—

The shaft 59 has a cam 82 fastened to it, the position of which longitudinally on said shaft may be best seen in Fig. 1. Referring now to Figs. 9 and 10, the cam 82 is generally circular, but at the extremities of a diameter, the cam is flattened forming parallel chord portions 83, 83. A lever 84, pivoted at 85 on the unit 11, provides a roller 86 in contact with the cam 82; the lever 84 also provides an inclined portion 86^a the purpose of which will presently appear.

All three of the posts 79, 80 and 81 are held by brackets 87, 88 and 89, respectively. These brackets are adapted to hold the posts at any height desired, set screws being provided for the purpose. The brackets do not completely surround the posts, but are cut away on the inside; thus the posts alone, and not the brackets, contact with the workpieces. The brackets 87 and 89 which hold the posts 79 and 81 are adjustably fastened to a member 90, which is pivoted at 91 to the stationary cover plate 92 (provided for the purpose of excluding dirt), which forms part of the unit 11. The member 90 provides a boss 93 in which is mounted a vertical pivot stud 94. Two lever arms 95 and 96, are mounted on this stud, the arm 95 serving to hold the third bracket 88. The arm 96 provides an adjusting screw 97 which is adapted

to contact with a surface 98 on the arm 95; a coil spring 99, surrounding the hubs of the two arms 95 and 96, tends to hold said arms together.

Extending downwardly from the member 90 is a forked pivotal post 100, providing a pivotal mounting for a lever 101. On the bottom of the lever 101 is a roller 102, which, when the cam surface 86^a is raised, is pressed outwardly thereby, thus rocking the lever 101 clockwise, Fig. 10. The upper end of the lever 101 contacts with the lever arm 96, and when the lever 101 is actuated as described, the arm 96 is therefore moved to the right, Fig. 10; the latter, in turn, exerts a similar turning movement on the lever 95, directly through the screw 97. The bracket 88 and the post 80 are thus pressed towards the posts 79 and 81, and this action clamps the workpieces in the magazine. When all three posts are contacting the workpieces, there can be no further relative movement between them, and further movement of the lever 101 serves to turn the whole magazine unit about the pivot 91 of the member 90. It will readily be seen that the pressure of the posts against the workpieces is proportionate to the weight of all these magazine parts, including the weight of the workpieces in the magazine, for the upper end of the lever 101 exerts more and more clamping force as it is moved until the reaction becomes substantially equal to the force exerted at the roller 102, due to the combined weight acting around the pivotal point 91 (the two arms of the lever 101 are substantially equal in this embodiment of the invention) when this equality is obtained the magazine unit lifts. The action is shown diagrammatically in Figs. 19 and 20.

When the shaft 59 is stationary, the cam 82 is in the position shown in Fig. 9, and the bottom workpiece is consequently free and drops into the appropriate aperture 78 provided in the work carrier plate 30, for, of course, the carrier cannot be moving when the shaft 59 is stationary, which is most of the time. But as the shaft 59 starts moving, the superimposed workpieces in the magazine are lifted off of the workpiece which is moved by the carrier plate, and in order that this lifting action may occur before any appreciable movement of the plate occurs, the screw 97 is tightened to allow practically no clearance between the posts and the workpieces; thus, the instant the shaft 59 and cam 82 start to move, said workpieces are gripped and lifted.

Referring to Figs. 2 and 3, the shaft 59 also has fastened to it a cam 103 which controls the energization and deenergization of the magnetic chuck 14. As actually constructed in this embodiment of the invention, the cams 82 and 103 are fastened together by a screw 104, the cam 103 being keyed to the shaft 59. Pivotedly mounted at 105 in a

box like structure 106 is a switch member 107. The pivot shaft 105 extends outside the box 106 and is surrounded by a coil spring 108. An arm 109, fastened to the shaft 105, provides a roller 110 that is in contact with the periphery of the cam 103. It is not deemed necessary to describe the exact manner in which the chuck is energized and deenergized, as such is well known in this class of machine; suffice it to say that the chuck must be de-energized when the carrier is moving and energized when the workpiece is being ground, and this is accomplished by controlling the chuck from the shaft 59 which controls the movement of the carrier.

Although the mechanism so far described is complete it itself and sufficient for the automatic grinding of round workpieces which are stacked in the magazine, it is nevertheless desirable to cause the grinding wheel 5 to be given a slight horizontal traversing motion so that a groove will not be worn in the said wheel. For that purpose, a pair of adjustable reversing dogs 111 and 112 are mounted on the carriage 2, being positioned to strike a reversing member 113 and thus reverse the direction of travel of the table 2. The reversing member 113 is connected to a valve member 114 which may be seen in the fluid pressure diagram of Fig. 17, the parts connected with said reversing valve 114 being shown in true section in this figure. It is not necessary to further describe the fluid pressure mechanism which, responsive to the movement of the valve 114, transverses the table 2 back and forth, as such mechanism is well known in machines of this class.

In order to keep the wheel 5 sharp and true, provision is made for dressing it periodically. As shown in Fig. 1, a dressing device 115 is mounted in the unit 11 and partakes of the vertical movements of adjustment of said unit. The device 115 is, of course, independently adjustable, and is carried in a threaded member 116 for that purpose. The left hand table dog 111, instead of being a fixed dog, like the right hand dog 112, is pivotally mounted and capable of being lifted, either manually or automatically, above the end of the reversing lever 113. When so lifted, the table 2 undergoes amplified movement to the right, thus carrying the grinding wheel 5 past the dressing device 115 which is located in its path of movement; thus said wheel is dressed and trued. Prior to contact between the grinding wheel and the dresser, however, the unit is automatically raised by a small amount, thus insuring a substantial contact between said wheel and dresser. As shown in Fig. 1, a cam member 117 adjustably attached to the table 2 is adapted to engage and depress a roller 118 carried on the end of a lever 119. The lever 119 is connected

to another lever 119^a which, by means of a link 120, operates a pawl 121. Referring now to Figs. 11 to 14 inclusive, the pawl 121 is carried on the end of a short shaft 122, which pivotally connects the link 120 to an arm 123 journaled around the shaft 124, to which the hand wheel 13 is attached. The shaft 122 provides a pin 125 located back of the link 120, said pin contacting with an adjustable guide member 126, by means of which the pawl can be caused to move a ratchet wheel 127 a variable amount. These parts are best seen in Fig. 13. As shown in the sectional view of Fig. 14, a spring pressed plunger 128, pressing against a flat portion of the shaft 122, causes the pin 125 to follow a stud 129 carried by the guide member 126.

The ratchet wheel 127, is thus turned through an angular distance which is adjustable, and as the ratchet wheel 127 is attached to the shaft 124, the latter is turned. The shaft 124 can be seen in Fig. 15; it carries a worm 130 which meshes with a helical gear 131 on a vertical screw shaft 132. The latter passes through an internally threaded member 133 that is fastened to the unit 11, and thus when the shaft 132 is turned, the unit 11 is raised.

Raising of the unit 11 raises the dressing device 115, but inasmuch as the magnetic chuck 14 is raised by an equal amount, the relation between the lower part of the periphery of the wheel 5 and the chuck 14 will not be changed, and the workpieces will be ground to a fixed and predetermined size. This dressing operation can be performed more or less frequently, depending on the accuracy with which the workpieces have to be ground. It seems scarcely necessary to observe that the motor 22 must be stopped during the dressing, in order that the head 4 may be at its bottom position, the motor being stopped when it is in such position. In a co-pending application Serial No. 208,263, filed July 25, 1927, an automatic means for effecting the above is described and claimed.

From the foregoing it will be seen that we have provided a greatly improved drive for the work carrier plate and an effectual means of preventing detrimental scratches in the already ground surfaces of the workpieces. In the developed cam surface as shown in Fig. 8, it will be noticed that the path of the cam 70 is so formed that a portion 134 of it gives the appropriate roller a slight rotary motion in advance of its being taken up by the closed path 135. Also, referring to Fig. 5, the arm 61 provides a plug 136 which extends on both sides thereof, and is adapted to partially close the respective ports 56^a and 57^a whichever one is, at that moment, the fluid exit port, and thus the movements of the work carrier actuating mechanism are accomplished without jar. It will be noted also, that the cam 70 serves to rigidly hold the work

carrier plate 30 during the time that the grinding operation is occurring; notwithstanding which, all the advantages of a cam motion are obtained for the mechanism, that is to say, gentle acceleration and possibility of accurate timing.

The mechanism which lifts the magazine and prevents scratches on the ground surfaces of the workpieces operates to force the posts 10 79, 80 and 81 together with a certain minimum force which is not sufficient to deform even thin walled workpieces; as the magazine is filled up, the force is increased in a definite ratio to the weight of the articles in the magazine, but the holding pressure is, under such circumstances, resisted by not one but many workpieces. Similarly, heavy workpieces will be gripped with a greater force in order to hold their weight, it being obvious that they 20 can withstand such a greater force without deformation.

We claim:

1. In a grinding machine, the combination with a magazine for holding a stack of 25 articles to be ground, and a carrier plate below said magazine to transfer the articles one by one, to a position where they may be operated upon by a grinding wheel, of means for lifting the magazine when the carrier 30 plate is operated.

2. In a grinding machine, the combination with a magazine for holding a stack of articles to be ground, and a carrier plate below said magazine to transfer said articles, 35 one by one, to a position where they may be operated upon by a grinding wheel, of means for lifting all but the bottom article in the magazine while said bottom article is being moved by said carrier plate, in order to prevent scratching of said articles by said plate.

3. In a grinding machine, a plurality of posts comprising a magazine for a stack of articles, an intermittently rotating carrier plate to transfer said articles, one by one, 45 to a chuck for a grinding operation, and means for urging said posts towards each other while said carrier plate is moving.

4. In a grinding machine, a plurality of posts comprising a magazine for a stack of 50 articles, an intermittently rotating carrier plate to transfer said articles, one by one, to a chuck for a grinding operation, means for forcing said posts together while said carrier plate is moving, and means for causing said force to be approximately proportionate to the weight of the stack of articles.

5. In a grinding machine, a plurality of posts comprising a magazine for a stack of 60 articles, an intermittently rotating carrier plate to transfer said articles, one by one, to a chuck for a grinding operation, means for forcing said posts together while said carrier plate is moving, and further means for lifting said posts, whereby the stack of 65 articles may be held by the magazine and

lifted from the carrier plate to prevent scratching of the bottom article.

6. In a magazine for grinding and like machines, a plurality of posts, a common support for said posts, a pivotal mounting 70 for said support, said pivot lying outside the area enclosed by said posts, one or more of said posts being movable relative to the other or others, and means for pressing the movable post or posts toward the other or others, the point of pressure being located above the plane of the aforesaid pivot, whereby articles in said magazine are first held by said magazine and then lifted.

7. In a grinding machine, the combination 80 with a magazine and a carrier plate for transferring articles successively to a grinding position, of intermittently operating mechanism for operating said carrier plate, and fluid pressure operating means for operating 85 said intermittently operating mechanism.

8. In a grinding machine, the combination with a magazine and a carrier plate for transferring articles successively to a grinding position, of a vertical shaft to which said carrier is attached, a member carrying a plurality of projecting elements also attached to said shaft, a cylindrical cam fitting between two of said projecting elements, and 95 means for intermittently rotating said cam, whereby to shift said carrier plate.

9. In a grinding machine, the combination with a magazine, a magnetic chuck and a carrier plate for transferring articles successively to said chuck, of a rotor, means for intermittently oscillating said rotor, means for transferring said intermittent oscillatory movement to intermittent unidirectional actuation of said carrier plate, and means also 100 under the control of said rotor for energizing and de-energizing said chuck.

10. In a grinding machine, the combination with a magazine and a carrier plate for transferring articles successively to a grinding position, of a rotor, means for intermittently oscillating said rotor, means for transferring 110 said intermittent oscillatory movement to intermittent unidirectional actuation of said carrier plate, and means also under the control of said rotor for periodically lifting the articles in said magazine.

11. In a grinding machine, the combination with a magazine, a magnetic chuck and a carrier plate for transferring articles successively to said chuck, of a rotor, fluid pressure means for intermittently oscillating said rotor, means for transferring said intermittent oscillatory movement to intermittent unidirectional actuation of said carrier plate, 125 and means also under the control of said rotor for energizing and de-energizing said chuck.

12. In a grinding machine, the combination with a magazine, and a carrier plate for 130

- transferring articles successively to a grinding position, of a rotor, fluid pressure means for intermittently oscillating said rotor, means for transferring said intermittent oscillatory movement to intermittent unidirectional actuation of said carrier plate, and means also under the control of said rotor for periodically lifting the articles in said magazine.
- 5 10 13. In a grinding machine, the combination with a magazine and a carrier plate for transferring articles successively to a grinding position, of a cylindrical cam, projecting elements connected to said carrier plate, said 15 elements fitting between surfaces on said cam, whereby said carrier plate is positively controlled by movement of said cam, and mechanism adapted to move said cam always to a given position.
- 20 14. In a grinding machine, the combination with a magazine and a carrier plate for transferring articles successively to a grinding position, of a cylindrical cam, projecting elements connected to said carrier plate, said 25 elements fitting between surfaces on said cam, whereby said carrier plate is positively controlled by movement of said cam, ratchet and pawl mechanism to actuate said cam, and a
- spring pressed member cooperating with notches to insure the movement of said cam 30 always to the same position.
15. In a grinding machine, the combination with a magazine and a carrier plate for transferring articles successively to a grinding position, of oscillatory actuating mechanism for said carrier plate comprising a semi-circular chamber, an arm therein, and means for admitting fluid under pressure first to one side and then to the other side of said chamber.
- 35 40 16. In a grinding machine, the combination with a magazine and a carrier plate for transferring articles successively to a grinding position, of oscillatory actuating mechanism for said carrier plate comprising a semi-circular chamber, an arm therein, means for admitting fluid under pressure first to one side and then to the other side of said chamber, and fluid pressure cushioning means whereby said carrier plate is moved without 45 50 shock.

Dated this 6th day of June, 1927.
